UNITED STATES PATENT OFFICE.

MATTHIAS BROCK, OF BOSTON, MASSACHUSETTS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

MACHINE FOR USE IN THE MANUFACTURE OF SHOES.

Application filed October 20, 1917, Serial No. 197,729. Renewed March 20, 1922. Serial No. 545,347.

This invention relates to machines for use in the manufacture of shoes and has for its object to produce a machine for locating the uppers and soles of shoes in proper relation to each other with or without pressing together the flanges of the uppers and the margins of the soles while they are in position to be secured. The invention, in its broader aspects, is applicable to the manufacture of shoes of various kinds and is shown herein, by way of illustration, in its particular application to stitchdown work. In a commercial method of making stitchdown shoes the upper is molded to present an outwardly projecting flange and the upper, and a sole or insole having an extension are assembled and the flange of the upper is sewed to the extension of the sole or insole before the last is inserted in the shoe. The sewing machine operator has to position the edge of the flange and the edge of the sole while the sewing operation is progressing, and it is only by the exercise of great skill that satisfactory work can be done and the production of uniform work by this method can be obtained, if at all, only at the sacrifice of reasonable speed.

By the aid of this invention the stitchdown manufacturing process can be expedited and better work secured than where each sewing machine operator is required to assemble his own work. As I am advised, it is new to provide a machine comprising means by which a sole and the flange of a previously molded upper may be accurately located in proper relation to each other off the last and then pressed together and secured.

An important feature of the invention consists in a novel organization of instrumentalities comprising means for locating a sole in a predetermined position, and means for locating an upper off the last in predetermined relation to the sole. In the illustrated embodiment of the invention the upper and the sole are preliminarily located out of intimate contact with each other, and the machine, as another feature, includes means for pressing together the flange of the upper and the margin of the sole. By application of cement to one or both of the contacting work faces this pressure may be caused to effect adhesion of the sole and flange surfaces sufficient to maintain them

in relative position until they are presented to the sewing machine. Preferably the upper is located relatively to the sole by means engaging the inside of the upper, for example, by a form having the contour which it is desired the end of the shoe shall have, and means co-operating with the inside form is provided for holding the upper in contact therewith about its periphery. This latter means may also form the means for pressing the flange against the margin of the sole.

A further feature of the invention consists in means for positioning the sole comprising means for embracing an end of the sole, and means capable of length adjustments for locating the other end of the sole laterally, the toe and heel end locating means being interconnected to effect width adjustments of one end locating means, for example that for the toe end, in accordance with length adjustments of the other end locating means, for example that for the heel end.

Another feature of the invention consists in means for locating a sole in predetermined position and upper locating means arranged for movement into and out of operative relation to the sole locating means in a predetermined path so that an upper and a sole may be brought into proper relation to each other. The upper locating means may comprise a form adjustable as to width and having the end and side contour of a last. In the embodiment of this feature herein shown, the form is for the toe end and is low as compared to a last of ordinary shoe shape, so that uppers having their toes molded to any height may be accommodated. Adjusting means is provided for varying the width of the form for various sized uppers, and size indications are provided for showing the size to which the adjusting means has been set.

Another feature of the invention consists in the combination with means for effecting size adjustments of the form, of means arranged to be shifted at the will of the operator for effecting a change in all of the size adjustments to accommodate the machine for treatment of uppers of the same range of sizes but of a different width.

Another feature of the invention consists in means co-operating with the form, comprising means for locating the exterior of the upper to hold the upper yieldingly

against the form or interior locating means, the said means for pressing the upper against the form being preferably power operated yieldingly to advance for pressing the upper 5 against the end of the form and to close for pressing the upper against the sides of the form. The pressing means is also preferably arranged to be retracted yieldingly to avoid disturbance of the upper in case the 10 pressing means should stick to the upper, which it might do should it receive accidentally upon it some of the cement used to secure the flange of the upper to the sole. The means for locating the upper against 15 the sides of the form also constitutes an element of the flange pressing means, power means including a yielding element being provided to actuate the sole support and the flange pressing means relatively to cause the 20 flange to be firmly pressed against the sole.

These and other features of the invention will appear more fully from the following description when read in connection with the accompanying drawings and will be pointed 25 out in the appended claims.

Fig. 1 of the drawings is a side view of the machine;

Fig. 2 is a plan view of the machine;

Fig. 3 is a detail of the flange pressing 30 means;

Fig. 4 is a sectional view on the line 4—4 of Fig. 2;

Fig. 5 is a perspective detail of the mechanism for closing the flange pressing means;

Fig. 6 is a plan view, partly in section, of 35 the sole locating mechanism;

Fig. 7 is a detail view in perspective of the upper locating device; and

Fig. 8 is a detail of parts shown in Fig. 7 40 in a different position.

Referring to Fig. 1, the frame of the machine is indicated by the numeral 2. In this frame is journaled a shaft 4 and a drive wheel 6 connected by a one-revolution clutch 45 with the shaft 4. The clutch is operated by a treadle rod 8 which also controls a brake 10. On the shaft 4 is a gear 12 meshing with a gear 14 on the shaft 16, the ratio of the gears 12 and 14 being two to one.

It will be noted from Fig. 2 that the illustrated machine is double or duplex, there 50 being two mechanisms operated from the same shaft which are identical except that one is reversely arranged with respect to the other, one being designed for treating the parts of a right shoe and the other for treating the parts of a left shoe. The mechanism at the right of the machine will now be described, it being understood that the other 55 mechanism operates in a similar manner but has its operating eccentric positioned 180° from the eccentric operating the right-hand mechanism. The right hand mechanism is designed to operate upon the parts of a left 60 shoe.

On the shaft 16, Fig. 4, is an eccentric 18 carrying an eccentric strap 20 pivoted at 22 to a plunger 24 arranged for sliding movement in a sleeve 26. The relative movement of the plunger 24 and the sleeve 26 is limited by a pin 28 in the plunger engaging a slot in the sleeve 26. In the upper end of the sleeve 26 is a screw 30 having a head to form a bearing for a spring 32 which bears at its other end upon the plunger 24. Through 70 this mechanism the thrust of the plunger 24 effected by the eccentric 18 is transmitted yieldingly to the sleeve 26. On the upper end of the sleeve 26 is a table 40 upon which the sole locating mechanism is adjustably mounted. The table is guided in its movement by a bar 41 bolted to the frame and engaging a suitable guideway in the table. On the table 40 are positioning pins 42 which engage holes in a plate 44. The plate 44 is slotted at its central portion to receive a screw 46 which passes through the slot into a member 48 which carries the sole locating mechanism. By loosening the screw 46, the member 48 may be adjusted relatively to the 75 table 40. In the member 48 is mounted a slide 50 having at its outer end a block 52 provided with a V-shaped notch 54 for locating the rear end of a shoe sole. The slide is held in the member 48 by a cover plate 49. A friction stud 55, Fig. 4, is provided in the table 40 to engage the slide 50 and hold it 80 yieldingly in adjusted position. The opposite end of the slide 50 is provided with divergent slots 56 which are engaged by pins 58 on plates 60, 62 which carry the means for positioning the forepart of the shoe sole. The plates 60, 62 are pivoted to each other and to the member 48 at 64 and are shown in 85 Fig. 6 in closed position. As the slide 50 is moved outwardly to receive a larger sole, the slots 56 act upon the pins 58 to reparate the plates 60, 62 about their pivot 64 so that the plates 60, 62 are separated an amount corresponding to the size of the sole 90 as indicated by the increased length. It will be seen that the plates 60, 62, as shown in Fig. 6, have an edge contour corresponding to that of a left shoe sole. On the edge faces of the plates 60, 62, are mounted members 70, 72 for locating the toe portion of the sole in 95 predetermined position. The sole locating members 70, 72 are slotted to receive screws 74 which hold them, respectively, to the edge faces of the plates 60, 62 but permit movement of the members 70, 72 in a direction perpendicular to the top faces of the plates 60, 62. To maintain the members 70, 72 normally in raised position to receive the edge face of the toe of a shoe sole thrust against them, springs 76 are provided which engage lugs 78 on the members 70, 72 and rest at their lower ends on portions 80 of the member 48.

A stitch-down upper which has previous-

ly been molded at its toe end with an outwardly projecting flange is to be located relatively to a sole on the sole locating means already described in position to have its outwardly directed flange pressed against the margin of the sole. For this purpose a form is provided having the contour of the side and end faces of the toe portion of a right or left last. The construction and mounting of the form is best shown in Figs. 2 and 7. Referring to Fig. 7, the form consists of two parts 90, 92 which are arranged for separation, about a virtual pivot located at their toe ends, by means of curved guides 94 and 96 which engages a slot formed in a supporting plate 98. The parts 90, 92 are held toward each other by a spring 100 attached by pins 102, 104 between the parts 90, 92. To separate the parts 90, 92 of the form for different sized uppers, a slide 106 is provided which has a pin 108 engaging a spiral groove 112 in an adjusting cam 110. On the upper face of the adjusting cam 112 is a plate 114, shown at the left of Fig. 2 and removed at the right in that figure, which is provided with size indications cooperating with an index 116 to indicate the proper setting of the cam for different sized uppers. The inner end of the slide 106 is provided with a shiftable member 120 which has opposite faces 122 to engage inclined faces 124, 126 on the parts 90, 92, respectively. Above the faces 124, 126 are overhanging flanges 128, 130 which overlie the member 120. The part 120 and the slide 106 are provided with interengaging means, as shown in Figs. 7 and 8, which prevent relative movement of these parts longitudinally of the slide but permit the part 120 to be lifted out when the parts 90, 92 are separated to displace the flanges 128, 130 from above the part 120. The part 120 is adapted to be shifted to a position 90° from that shown in Fig. 7 and to be re-engaged with the slide, as shown in Fig. 8. The member 120 is preferably marked with width indications, the marks D and E being shown in the drawings. When the portion marked D is in engagement with the slide 106, the ends 122 which engage the parts 90, 92 are less widely separated than when the portion marked E is put in engagement with the slide 106. Therefore, provision is made for initially setting the parts 90, 92 of the form for a given width, the size adjustments for that width being effected by rotating the cam 110. The form 90, 92 is mounted for convenient movement into and out of position over the toe end of the sole locating means, and when in position over the sole locating means its location laterally thereof is accurately determined. The supporting plate has riveted to it two arms 132, 134 which are connected by parallel links 136 to a rocker 138 having a trunnion 140

mounted in the frame of the machine, Fig. 1. To the rear end of the trunnion 140 is attached an arm 142, the lower end of which is held inwardly yieldingly by a spring 144. To limit this movement of the arm, a screw 146 threaded through a lug on the arm 142 and engaging a stop 147 on the machine frame is provided. By this construction the form 90, 92 is held yieldingly raised by the spring 144 so that it may be depressed toward the sole locating means and is movable into the machine from the position shown at the left of Fig. 2 to the position shown at the right in that figure by a swinging movement on the parallel links 136. 70 Co-operating with the form 90, 92 which determines the inside contour of the upper about the side and end portions of the toe is provided means for engaging the outside of the upper and holding it against the side 85 and end faces of the form. This means comprises, as best shown in Fig. 5, a pair of plates 150, 152 which are mounted on the under side of carriers 154, 156, and are removably held in place thereon by screws 90 158. In order that the plates 150, 152 close about a point located at the center of the toe, the carriers 154, 156 are arranged for movement about that center, their movement being guided by fixed pins 160 which 95 engage curved slots 162 therein. The pins 160 are headed at their lower ends and extend upwardly into lugs 161 in a transverse member 163 of the frame, Fig. 2. The carriers 154, 156 are thus movably secured to the machine frame. As shown in Fig. 3, the plate 150 on the carrier 154 is provided with a tongue 151 which engages a groove in the other plate 152. This constitutes a virtual pivot connection between 100 the carriers 154, 156 but slight separation of the plates is permitted at the junction should the shape of the work demand it. Movement is imparted to the carriers 154, 156 by links 166, 168 which are pivoted at their 110 forward ends to the carriers 154, 156 and have at their rear ends a common pivot 170 on a block 172 arranged to slide longitudinally of the form on a bracket 178 secured to the transverse member 163 of the machine frame. The block 172 is actuated by a bell-crank lever pivoted at 176 to the bracket 178. One arm 180 of the bell-crank lever is pivoted to the block 172 and the other arm 182 is pivoted to a block 184 through which 115 passes freely a rod 186 which at its lower end is secured to a rearwardly extending portion of the table 40, Fig. 4. An actuating spring 188 is mounted on the rod between the rearwardly extending portion of 120 the table 40 and the block 184, and above the block 184 a retracting spring 190 is provided which engages at its upper end a pin 192 passing through the rod 186. It will be seen that when the table 40 is raised by its 130

eccentric, the spring 188 will be compressed and will act through the bell-crank lever 180, 182 to move the block 172 forwardly and cause the links, 166, 168 to move the carriers 154, 156 toward the form 90, 92, and at the same time the pins 160 will act upon the slots 162 to effect the closing movement of the carriers about the form. To limit the closing movement of the carriers to correspond with the given adjustment of the form, a screw 196, is provided, the screw 196 having a knurled head 197 is threaded through the transverse member 163 and engages the arm 180 of the carrier actuating bell-crank lever.

In the operation of the machine the operator will withdraw the slide 50 and place a left shoe sole in contact with the means 70, 72 for positioning the toe end of the sole. He will then push in the slide to cause the V-shaped faces 54 of the part 52 to engage the heel end of the sole and locate it laterally. By this movement the toe locating means 70, 72 will be closed automatically to a size corresponding to the length of the sole. During the positioning of the sole, the form 90, 92 is swung back and to one side on its parallel links 136, as shown at the left in Fig. 2. The operator will now adjust the form by turning the cam 112 until the size corresponding to that of the upper comes opposite the index 116. He will also see that the member 120 is positioned on the slide 106 to correspond with the width of shoe being operated upon. The upper, which preferably has already been molded to approximately the proper shape at its toe end and has an outwardly extending flange coated with a suitable adhesive, is placed over the form 90, 92 and depressed by turning the rocker 138 against the tension of the spring 144 until the form is adjacent to the sole. The form and upper are then swung in until the upper engages the plates 150, 152 at its toe end. The treadle is now depressed to start the machine whereupon the shaft 16 makes a semi-rotation, bringing the parts into the position shown in Fig. 4. During this movement the table 40 has been yieldingly raised through the spring 32 and the spring 188 has acted through the connections described to cause forward and closing movement of the plates 150, 152 about the toe of the upper to press it into engagement with the form. The movement of the plates will, of course, be effected before the table has reached the limit of its upward movement and during the latter part of that movement the sole will be forcibly pressed against the flange of the upper which is supported on its top face by the plates 150, 152.

Having fully described my invention, what I claim as new and desire to secure by Letters Patent of the United States is:—

1. In a machine for assembling a previ-

ously molded stitch-down upper having an outwardly extending flange in proper relation to a sole to be secured thereto, the combination of means for locating the sole in predetermined position, and means constructed and arranged to shape and hold the molded upper peripherally in proper predetermined relation to the sole by engagement with the inner and outer faces of the upper over an area confined to the side and end portions of the upper adjacent to the outwardly extending flange, said means having parts arranged for relative movement at first substantially parallel to the sole and then perpendicularly to the sole.

2. In a machine for assembling a previously molded stitch-down upper having an outwardly extending flange in proper relation to a sole to be secured thereto, the combination of means for locating the sole in predetermined position, means having the peripheral contour of the inner side of the toe portion of a shoe over which means the upper is placed, said means being formed to occupy a portion only of the space enclosed by the upper, and means arranged to close upon the upper for holding the upper to said peripheral contour to determine the shape of the upper and to locate the flange of the upper in proper relation to the sole in the locating means for attachment of the flange of the upper and the margin of the sole.

3. In a machine for assembling a previously molded stitch-down upper having an outwardly extending flange in proper relation to a sole to be secured thereto, the combination of means for locating the sole in predetermined position, a flat form having the peripheral contour of the inner side of the toe portion of a shoe over which means the upper is placed and providing a space over the toe of the form between the form and the upper, means for holding the upper to said peripheral contour to determine the shape of the upper and to locate the flange of the upper in proper relation to the sole in the locating means for attachment to the flange of the upper and the margin of the sole, and means for relatively moving said sole locating means and said upper shaping means substantially perpendicularly to the sole to cause the flange to be secured to the margin of the sole by cement.

4. In a machine of the class described, the combination with sole locating means, of upper locating means comprising a form having the edge and side contour of a last but not the height of a last arranged for insertion into an unlasted upper having an outwardly extending flange and arranged for movement longitudinally of a sole in said locating means in a predetermined path.

5. In a machine of the class described, the combination with sole locating means, of up-

per locating means comprising a form lower than a last and having the edge and side contour of a last arranged for insertion into an unlasted upper having an outturned flange, upper clamping means comprising parts movable parallel to the bottom of said form and having an edge contour corresponding to that of the form, and means for closing the clamping means to conform the upper to the side faces of the form.

6. In a machine of the class described, the combination with sole locating means, of upper locating means comprising a form having the edge and side contour of a last arranged for insertion into an unlasted upper having an outturned flange, upper clamping means having an edge contour corresponding to that of the form, means for closing the clamping means to conform the upper to the side faces of the form, and means operating in time relation with said closing means for moving relatively the sole locating means and the clamping means to clamp the outturned flange against the sole on the sole locating means.

7. In a machine of the class described, the combination with sole locating means and upper locating means comprising a form having the end and side contour of a last arranged for insertion into an unlasted upper having an outturned flange, of upper clamping means having an edge contour corresponding to that of the form, and power means for closing the clamping means yieldingly against the end and sides of the form to shape the upper to the toe portion of the form.

8. In a machine of the class described, the combination with sole locating means and upper locating means comprising a form having the end and side contour of a last arranged for insertion into an unlasted upper having an outturned flange, of upper clamping means having an edge contour corresponding to that of the form, power means for closing the clamping means yieldingly against the end and sides of the form to shape the upper to the toe portion of the form, and power means for relatively moving the clamping means and the sole locating means to cause a sole on the locating means and the flange of the upper underlying the clamping means to be pressed together.

55 9. In a machine of the class described, the combination of sole locating means having a flange extending about the periphery of the toe end of a sole to locate the toe end of the sole, said flange being arranged for movement perpendicularly to the bottom of the sole, and means for locating the heel end of the sole.

10. In a machine of the class described, the combination with sole locating means to locate the toe end of a sole, of means for

locating the heel end of the sole which is adjustable for varying lengths of soles, and connected means for causing the width of the toe end locating means to be varied in accordance with the length adjustment of the means for locating the heel end of the sole.

11. In a machine of the class described, the combination with sole locating means having a flange arranged for movement perpendicularly to the sole to locate the toe end of a sole, of means for locating the heel end of the sole, and means for pressing the outturned flange of a previously molded stitch-down shoe upper upon a sole located in the sole locating means.

12. In a machine of the class described, the combination of a widthwise adjustable form for determining the edge contour of an unlasted shoe upper having an outturned flange, and means for pressing a sole and the outturned flange of said upper into contact to effect adhesion of cement on the engaging faces of the sole and flange to secure the upper and sole together.

13. In a machine of the class described, the combination of a widthwise adjustable form for determining the edge contour of an unlasted shoe upper having an outturned flange, means having size indications for setting the form for a given size, and means for pressing a sole and the outturned flange of said upper into contact to effect adhesion of cement on the engaging faces of the sole and flange to secure the upper and sole together.

14. In a machine of the class described, the combination of an adjustable form for determining the inside edge contour of an unlasted shoe upper, means for adjusting the form for varying sizes all of a designated shoe width, and means shiftable at will for adapting the adjusting means to effect adjustment of the form for the same sizes of a different shoe width.

15. In a machine of the class described, the combination of an adjustable form for determining the inside edge contour of an unlasted shoe upper with means for presenting a sole in position for connection with an outturned flange of an upper supported by the said form, means for adjusting the form for a series of sizes all of one shoe width, and means shiftable at will for adapting the adjusting means to effect adjustment of the form for the same series of sizes of another shoe width.

16. In a machine of the class described, the combination of upper locating means comprising a low form having the edge and side contour only of a last and arranged for insertion into an unlasted upper having an outturned flange, and upper clamping means having a thin edge contoured to correspond to the shape of the form and a face

to engage the flange so that said clamping means applies pressure to the flange and avoids pressure against a substantial area of the form.

5 17. In a machine of the class described, the combination of a sole locating means, upper locating means comprising a form having the edge and side contour only of a last and arranged for insertion into an 10 unlasted upper having an outturned flange already formed thereon, upper clamping means having an edge contour corresponding to that of the form, means for closing the clamping means to conform the upper 15 to the side faces of the form, and means for limiting the closing movement of the clamping means to avoid excessive pressure of the clamping means against the form, the sole locating means and the clamping means being relatively movable to clamp the outturned flange against a sole in the sole locating means.

18. In a machine of the class described, the combination of sole locating means, upper locating means comprising a form adjustable for different sizes and having the edge and side contour of the toe end of a last, said form being arranged for insertion in an unlasted shoe upper having an 25 outturned flange, upper clamping means arranged to embrace the form and to close to conform the upper to the periphery of the form, means for adjustably limiting the closing movement of the clamping means to correspond with the size adjustments of the form, and means for moving relatively the sole locating means and the clamping means to clamp the outturned flange of the upper 30 against a sole on the sole locating means.

40 19. A machine for use in assembling the uppers and soles of stitch-down shoes, having, in combination, means engaging the inner and outer faces of the end and sides only of the upper and the edge of the sole 45 for locating the uppers and soles in proper relation to each other, and means for effecting relative movement between the outturned flange of the upper and the margin of the sole perpendicularly to the sole bottom to press the upper and sole together.

50 20. A machine for use in assembling the uppers and soles of stitch-down shoes, having, in combination, means for engaging the sole, and means for relatively locating an upper having an outturned flange in proper relation to the sole by contact only with the inner and outer faces of the end and sides of the upper and holding the upper in position for the flange to be attached to the 55 margin of the sole and power means for causing relative movement between the locating means and the sole engaging means to press the flange and sole margin together.

60 21. In a machine of the class described, the combination of means for locating the

heel end of a sole, means for locating the toe end of the sole comprising a flange extending about the periphery of the toe end of the sole mounted for movement perpendicularly to the bottom of the sole, and means for pressing the outturned flange of an upper against the sole arranged to engage and depress said toe locating means.

65 22. In a machine of the class described, the combination of means for locating a shoe sole in predetermined position off the last, means for locating a shoe upper off the last in predetermined position relatively to the sole including a form constructed and arranged to receive the shoe upper upon it, upper clamping means having a contour conforming to that of the sides and end of the form, and means for closing the clamping means against the sides and end of the form to shape the upper to the form.

70 23. In a machine of the class described, the combination of means for locating a shoe sole in predetermined position off the last, means for locating a shoe upper off the last in predetermined position relative to the sole including a form constructed and arranged to receive the shoe upper upon it, and means having the general contour of the end and sides of the form for pressing the upper against the contour surface of the 75 end and sides of the form and forcing the margin of the upper and the surface of the shoe sole against each other.

75 24. In a machine for co-relating a shoe upper and shoe sole off the last into the 80 relative positions they are to have in the finished shoe, the combination of means for placing the end of the shoe upper and the end of a shoe sole in predetermined relation including a form for receiving the end of the 85 upper and relatively positioning means for the shoe sole, and means for pressing the upper about the sides and end of the form and the margin of the upper and the shoe sole together.

90 25. In a machine for co-relating the end of a shoe upper and the end of a shoe sole off the last into the relative positions they are to have in the finished shoe, the combination of a form constructed and arranged to receive the end of the shoe upper upon it, means for positioning the shoe sole in predetermined relation to the form, means having an edge contour corresponding to that of the form for treating the upper 95 while on the form, and power means operating through yielding connections to actuate the treating means to conform the upper to the sides and end of the form and to press marginal portions of the end of the upper 100 and the shoe sole into contact with each other.

105 26. In a machine for co-relating the end of a shoe upper and the end of a shoe sole off the last into the relative positions they 110

- are to have in the finished shoe, the combination of means including a form for supporting the end of a shoe upper in predetermined position, means for predetermined 5 position of a shoe sole relative to the end of the shoe upper on the form, and means for conforming the upper to the contour of the sides and end of the form and laying a flange of the end portion of the upper on the surface of the shoe sole constructed and arranged to permit the joint removal of the related upper and sole. 10
27. In a machine for co-relating a shoe upper and shoe sole off the last into the relative positions they are to have in the finished shoe, the combination of means for placing the end of the shoe upper and the end of a shoe sole in predetermined relation including a form for receiving the end 15 of the upper and relatively positioning means for the shoe sole, and means for pressing the upper longitudinally and transversely about the sides and end of the form and the margin of the upper and the shoe sole against each other. 25
28. In a machine of the class described, the combination of clamping means, means comprising a compressible member for locating a shoe part in predetermined relation to the clamping means, and power means for operating the clamping means to clamp the shoe part and to cause depression of the locating means. 30
29. In a machine of the class described, the combination of a form having the end and side contour of an end of a last and upon which the end of the upper is located, means for locating a sole in predetermined relation to the form, upper treating means 35 having an edge contour corresponding to that of the form, and power means for operating the upper treating means to conform the upper to the end and sides of the form and to cause the margin of the upper and the margin of the sole to be pressed together. 40
30. In a machine of the class described, the combination of a form adapted to receive a shoe upper and having the contour of an end and sides of a last, means for locating a sole in predetermined relation to the form, clamping means having the contour of the form, and power operated means for moving the clamping means against the end and sides of the form and for forcing the margin of the upper and the margin of the sole bottom together. 45
31. In a machine of the class described, means for locating a sole in predetermined position, and upper locating means arranged for bodily movement laterally of the sole into and out of position over said sole locating means. 50
32. In a machine of the class described, means for locating a sole in predetermined 55 position, and upper locating means constructed and arranged for movement into position over said sole locating means in a predetermined path to locate an upper with its edge parallel to the periphery of the sole, 70 said locating means being constructed and arranged for bodily movement away from its position over the sole to an inoperative position for the reception of an upper. 75
33. In a machine of the class described, means for locating a sole in predetermined position laterally and longitudinally, and means for locating an upper relatively to said sole for attachment thereto comprising locating means, a support therefor, parallel links connecting the locating means and the support to provide for movement of the locating means in a predetermined path into and out of operative position over said sole and to cause the locating means when in operative position to locate an upper with its edge parallel to the sole in the locating means. 80
34. In a machine of the class described, the combination of sole locating means, upper locating means comprising a form having the end and side contour only of a last and arranged for insertion into an unlasted upper having a sole attaching flange already formed thereon, exterior upper locating means having an edge contour corresponding to that of the form, means for closing the exterior locating means to conform the upper to the end and side contour of the form, means for limiting the closing movement of the exterior locating means, and means for relatively moving the sole locating means and the upper locating means to force the upper and sole together. 85
35. In a machine of the class described, means for locating a sole in predetermined position, and upper locating means comprising a member arranged for movement in a plane substantially parallel to and above the sole, said member being arranged for permissive movement toward the sole. 90
36. In a machine of the class described, the combination of means for locating a sole in predetermined position, and means for locating an upper in predetermined relation to the sole, said means including a member having the peripheral shape of the end of the sole and being movable lengthwise of the sole in a plane substantially parallel to the sole and means for locating the periphery of said member in parallelism to the periphery of the sole. 105
37. In a machine of the class described, the combination of means for locating a sole in predetermined position, and upper locating means comprising a member having substantially the shape of the inner periphery of an end of a shoe upper, said member being mounted for movement into and out of operative relation to the sole positioning 115
- means for locating a sole in predetermined 120 position, and upper locating means constructed and arranged for movement into position over said sole locating means in a predetermined path to locate an upper with its edge parallel to the periphery of the sole, 125 said locating means being constructed and arranged for bodily movement away from its position over the sole to an inoperative position for the reception of an upper. 130

means in a predetermined path including components of movement laterally and longitudinally of the sole.

38. In a machine of the class described, means for locating a sole in predetermined position, and upper locating means comprising a member having the contour of an end of the sole arranged for movement in a plane substantially parallel to and above the sole, said member being arranged for movement manually toward the sole.

39. In a machine of the class described, the combination of means for locating a sole in predetermined position, and means for locating an upper in predetermined relation to the sole, said means including a member having the peripheral shape of the end of the sole and movable transversely of the sole in a plane substantially parallel to the sole, and means for locating the periphery of said member in heightwise alinement with the periphery of the sole.

40. In a machine of the class described, the combination of means for locating a sole in predetermined position, and upper locating means comprising a member having substantially the shape of the inner periphery of an end of a shoe upper, said member being mounted for movement into and out of operative position in a predetermined path including components of movement laterally and longitudinally of the machine.

41. In a machine of the class described, means for locating a sole in predetermined position, and upper locating means comprising a member arranged for movement transversely of and above the sole and for movement toward the sole.

42. In a machine of the class described, the combination of means for locating a sole in predetermined position, and means for locating an upper in predetermined relation to the sole, said means including a swinging member movable transversely of the sole in a plane substantially parallel to the sole, and means for locating the periphery of said member in heightwise alinement with the periphery of the sole.

43. In a machine of the class described, the combination of means for locating a sole in predetermined position, and upper locating means comprising a member having substantially the shape of the inner periphery of an end of a shoe upper, said member being mounted for movement into and out of operative relation to the sole, positioning means in a predetermined path including components of movement laterally and longitudinally of the machine.

44. In a machine for locating an unlasted stitchdown upper in relation to the end of a sole to which it is to be attached, the combination of means for presenting the sole, end embracing wipers constructed and arranged yieldingly to hold the upper to the shape of the periphery of the shoe end by engagement with the upper along a line in a plane substantially parallel to the sole, and power operated means for operating the wipers and for effecting relative heightwise movement of the wipers and sole to cause the upper to be pressed in outspread relation against the margin of the sole.

In testimony whereof I have signed my name to this specification.

MATTHIAS BROCK.
